15 1 designates a shank having at one end a curved extension 2, on the free extremity of which is a disk-shaped head 3. The curved portion of the shank is provided with a plurality of notches 4, while on the opposite end

of said shank is an approximately rectangular body 5, provided along one end edge and 20 one side edge with a chamfered or beveled portion 6. A V-shaped notch 7 is arranged along one of the longitudinal sides of said rectangular body portion and is provided with a chamfered edge 8. 25

What I claim, and desire to secure by Letters Patent, is—
